UNITED STATES PATENT OFFICE.

ARTHUR M. BENNER, OF OLYMPIA, WASHINGTON.

DRAWER.

Application filed November 29, 1920. Serial No. 427,668.

To all whom it may concern:

Be it known that I, ARTHUR M. BENNER, a citizen of the United States, residing at Olympia, in the county of Thurston and

State of Washington, have invented new and useful Improvements in Drawers, of which the following is a specification.

This invention relates to improvements in furniture and has for an object the provision of a case of drawers in which the said drawers are capable of opening from either end and provided with novel means for limiting their outward movement.

Another object of the invention is the provision of means for holding the drawers against accidental movement in either direction when in closed position, the said means being operable from either end to release the drawers, so that the latter may be opened in either direction.

Other objects and advantages of the invention will appear as the following description is read in connection with the accompanying drawings:

25 In the drawings:—

Figure 1 is a front elevation of a drawer cabinet embodying the present invention.

Figure 2 is a side view of the same with one drawer partly open.

30 Figure 3 is a horizontal section taken on a line with the means for limiting the outward movement of the drawer.

Figure 4 is a similar view taken on a line with the means for holding the drawer in closed position.

Figure 5 is an enlarged vertical sectional view on the line 5—5 of Figure 1.

Figure 6 is an enlarged side elevation of one of the drawers removed from the cabinet.

40 Figure 7 is a vertical sectional view on the line 7—7 of Figure 6.

Figure 8 is a fragmentary elevation of the interior of one of the side walls of the cabinet.

45 Referring to the drawings in detail, wherein like characters of reference denote corresponding parts, the invention is shown in the form of a cabinet which includes a casing 10. This casing may be of any suitable configuration to adapt it for the purpose intended, for example, it may be in the form of a cabinet for phonograph records, a bureau, chiffonier or table, or in fact any article of furniture containing one or more drawers. The cabinet herein shown in-

cludes a plurality of drawers which are mounted for sliding movement upon guides 11 secured within the cabinet, the said guides extending substantially flush with the edges 60 of the side walls 12.

The drawers which are indicated at 13 are capable of being opened from either end of the cabinet and include end members 14 which are connected by side walls 15 and a 65 bottom 16. The end members 14 are notched at each of their upper corners as indicated at 17 to provide room for the strips 11.

One of the side members 15 of each drawer is provided with a longitudinally arranged groove 18 which registers with a similar groove 19 formed in the adjacent wall of the cabinet and a block 20 has its opposite edges extending within the grooves 70 18 and 19. Thus, when the drawer is pulled open from one end of the cabinet the block will engage the opposite end of the groove 18 and the adjacent end of the groove 19 75 so as to limit the outward movement of the drawer. When opened from the opposite end, the block 20 will engage the opposite end walls of the grooves 18 and 19 from that previously mentioned so as to limit the movement of the drawer in an opposite direction. 80

Secured to one of the side walls 15 of the drawer and at each end thereof is one end of a spring arm 21. This arm is secured flush to the outer face of the member 15 and has its free end extending outward to provide a spring latch or stop 22, the extremity of which extends within the drawer and is connected to one end of a rod 23. The opposite end of this rod is pivotally secured to a plate 24, which is pivoted as indicated at 90 25 within a recess provided upon the inner face of the end member 14, the rod 23 being also located within a groove 26, so that the said plate and rod will not extend beyond the 95 inner face of the end member 14. Also pivotally connected to the plate 24 is a lifting element 27, the latter being guided in an opening 28 provided in the end member 14 and having one extremity bent for pivotal 100 connection with the plate 24 as shown at 29. The opposite end of the lifting element 27 is formed with a finger piece 30 which is located beneath an ordinary drawer pull 31 secured upon the outer face of the member 14. These parts are all duplicated at opposite ends of the drawer and if desired may 105 110

be also duplicated upon opposite sides for engagement with the opposite walls of the cabinet, while the invention may also be used in connection with a one-way drawer, 5 whereupon the spring latch will be located at one end of the drawer only. The upper edge of each of the end members 14 is preferably provided with a strip 32 which covers the upper end of the guide opening 28 and 10 provides convenient means for forming the notches 17, as the said strip may terminate short of each end of the end members 14 and thus render it unnecessary to cut away any portion of the said end members in the formation of the notches 17. Of course these notches are only necessary where more than one drawer is used.

When it is desired to open the drawer from either side of the cabinet, the fingers 20 of the hand have their ends positioned under the pull 31 whereupon the element 27 will be lifted to move the plate 24 upon the pivot 25. This will exert an inward pull upon the spring latch 22 which is connected 25 to the element 27 through the rod 23, so that the latter will be retracted from engagement with a recess 33 formed in the adjacent side wall of the cabinet. The drawer may then be moved outward, whereupon the spring 30 latch 22 at the opposite end of the drawer will be forced inward due to the engagement of its inclined portion with the end wall of the recess 33. In order to permit of this inward movement of the opposite spring latch 35 22, the rods 23 are formed in sections, the adjacent ends of which are linked together as indicated at 34, so that buckling will be prevented.

It will be seen from the foregoing description and the accompanying drawings,

that the invention provides means for holding a drawer in closed position without the necessity of a lock and key and for preventing the said drawer being pulled entirely out of the cabinet, at the same time 45 permitting the drawer to be opened from either end if desired. The invention is especially useful upon ships whose movement would tend to accidentally open the drawer, or upon moving vehicles, while it is also 50 convenient for use in restricted places where there is not sufficient room to pull out a drawer for its entire depth.

The invention is susceptible of various changes in its form, proportions and minor 55 details of construction and the right is herein reserved to make such changes as properly fall within the scope of the appended claim.

Having described the invention what is 60 claimed is:—

An article of furniture embodying a cabinet consisting of top, bottom and side walls, slotted guides arranged in parallel relation within the side walls, drawers slidingly 65 mounted therein and capable of being pulled outward in either direction, the side members of each drawer having a longitudinally arranged groove registering with the guides of the side walls, and a block having 70 its opposite ends extending within the guides and grooves to engage the opposite ends thereof to limit the outward movement of the drawer, and spring actuated arms for holding the drawer in closed position, said 75 arms having manually operated means connected thereto whereby the drawer may be released to permit of its being opened.

In testimony whereof I affix my signature.
ARTHUR M. BENNER.
